United States Patent Office

Des. 188,318
Patented July 5, 1960

188,318

SECTIONAL SOFA

Stanley J. Niederman, Chicago, Ill., assignor to Howard
Parlor Furniture Co., Chicago, Ill., a corporation of Illinois

Filed Mar. 1, 1960, Ser. No. 59,574

Term of patent 14 years

(Cl. D15—11)

FIG. 1

FIG. 2

FIG. 4

Fig. 1 is a front perspective view of a sectional sofa, showing my new design;

Fig. 2 is a top plan view of the same;

Fig. 3 is an end elevational view of the same as seen from the left-hand end of Figure 1, the opposite end of the article appearing the same but of the opposite hand; and

Fig. 4 is a rear elevational view of the same as seen from the left side of Figure 2, the rear view of the article as seen from the top of Figure 2 appearing the same but of the opposite hand.

I claim:

The ornamental design for a sectional sofa, as shown and described.
